UNITED STATES PATENT OFFICE.

JOHN A. MACMILLAN, OF DAYTON, OHIO.

DESIGN FOR A CORE FOR VEHICLE-TIRES.

46,884.

Specification for Design.

Patented Jan. 26, 1915.

Application filed September 10, 1914. Serial No. 861,153. Term of patent 14 years.

To all whom it may concern:

Be it known that I, JOHN A. MACMILLAN, a citizen of the United States, residing at Dayton, Ohio, have invented a new, original, and ornamental Design for a Core for Rubber Tires, of which the following is a specification, reference being had to the accompanying drawing, forming part thereof.

The drawing represents a perspective view of a section of a rubber core forming the interior cushion-support for the ordinary pneumatic outer shoe or casing of an automobile or motorcycle tire.

The characteristic feature of this invention is a continuous rubber tread portion supported by a central, continuous, annular,

vertical strut or bridge, which is flanked alternately at its sides, at intervals, by a curved, transverse, supporting truss shaped to fit the interior of the shoe or casing and joining the continuous tread and vertical bridge portions. The width of these trusses of rubber is increased or diminished in proportion to the load to be carried.

I claim:

The ornamental design for a core for vehicle tires, substantially as shown and described.

JOHN A. MACMILLAN.
